UNITED STATES PATENT OFFICE.

WALTER VON NESSEN, OF NEW YORK, N. Y., ASSIGNOR TO EFCOLITE CORPORATION, A CORPORATION OF NEW YORK.

DESIGN FOR A SHADE.

Application filed September 22, 1928 Serial No. 28,240. Term of patent 7 years.

To all whom it may concern:

Be it known that I, WALTER VON NESSEN, citizen of the German Republic, and a resident of New York, county of Bronx, and State of New York, have invented a new, original, and ornamental Design for a Shade, of which the following is a specification, reference being had to the accompanying drawing, forming a part hereof.

In the drawing:

Figure 1 is a front elevational view of the shade;

Figure 2 is a side elevational view of the same; and

Figure 3 is a top plan view of the shade.

I claim:

The ornamental design for a shade substantially as shown.

WALTER VON NESSEN.
